(57) **CLAIM**

The ornamental design for golf club head, as shown and described.

DESCRIPTION

FIG. 1 is a bottom, perspective view embodying the inventive design;

FIG. 2 is a top plan view thereof;

FIG. 3 is a heel-side elevational view thereof;

FIG. 4 is a front elevational view thereof;

FIG. 5 is a toe-side elevational view thereof;

FIG. 6 is a bottom plan view thereof; and,

FIG. 7 is a rear elevational view thereof.

The broken lines illustrate environmental structure that form no part of the claimed design.
